Primary Examiner — Shannon W Morgan*Assistant Examiner* — Keith Frank(74) *Attorney, Agent, or Firm* — Tucker Ellis LLP; Carlos Garritano(57) **CLAIM**

The ornamental design for a storage container, as shown and described.

DESCRIPTION

FIG. 1 is a perspective view of a storage container showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The evenly spaced and dashed broken lines in the drawings showing the storage container illustrate the portions of the storage container that form no part of the claimed design. The dash-dot-dash lines in the drawings represent boundary lines between claimed and unclaimed areas of the storage container.
